United States Patent

Des. 240,971
Patented Aug. 17, 1976

240,971

BOOT

James F. Summa, Naugatuck, and John R. White, Woodbridge, Conn., assignors to Uniroyal, Inc.

Filed Apr. 16, 1975, Ser. No. 569,231

Term of patent 14 years

Int. Cl. D2—04

U.S. Cl. D2—272

Fig. 1.

Fig. 2.

Fig. 3.

FIG. 1 is a right front perspective view of a boot showing our new design;

FIG. 2 is a left rear perspective view thereof;

FIG. 3 is a rear elevational view thereof;

FIG. 4 is an enlarged, fragmentary developed plan view of the repetitive patterned band which extends around the upper portion of the boot.

We claim:

The ornamental design for a boot, substantially as shown and described.
